Patent expires September 25, 1966

15 Claims. (Cl. 164—48)

1

This invention relates to wire feeding mechanism and is concerned more particularly with controlling the wire feed in wire stitching machines for the forming and driving single or double stitches.

Broadly, the invention consists in the provision of wire grippers associated with the wire feeding elements and adapted to grip the wire during the feeding stroke, and further wire grippers adapted to hold the wires after feeding is complete whilst the fed wires are being severed and the wire feeding elements are returning to the position for feeding a further length of wire, the various wire grippers being operated in the desired sequence and timed relationship to ensure positive control of the wire or wires at all times in the working cycle from leaving the spool until they are delivered to the stitch forming mechanism.

Furthermore the invention includes, in double-stitch feed mechanism, the provision for independently operable sets of grippers for each wire, and means whereby either wire may be immobilised at will or by automatic control so that either or both wires may be fed at the given times to place single and double stitches in various selected sequences as best suited to the work being operated on, all these controls being provided in such a form as to be independent of the particular setting for length of the wires being fed.

By the employment of mechanism according to the invention very reliable and accurate wire feeding is attained at the highest speeds, with the minimum possible wear of the wire feeding elements, and useful alternative methods of placing the stitches in the work can be provided for in the case of double stitch mechanisms.

The following are the requirements to be fulfilled by wire feed mechanism according to the invention: (1) Prior to the commencement of the wire feed motion and whilst the movable wire feeding elements are stationary, the wire grippers of these elements, hereinafter referred to as wire feed grippers must be mechanically closed on the wire, and simultaneously or immediately thereafter the wire grippers of stationary elements which prevent return motion of the wire during the return motion of the wire feeding elements, and hereinafter referred to as non-return grippers must be mechanically opened. The grip is thus transferred from the non-return grippers to the wire feed grippers whilst these and the wire are stationary, and on the forward motion of the wire-feeding elements the wires

2

are fed freely forward. (2) After the conclusion of the feeding stroke of the wire feeding elements and during a stationary period prior to the return of the wire feeding elements, the non-return grippers are closed and the wire feed grippers opened, the wire grip control now passing from the feeding elements to the non-return elements; during the return motion of the wire feeding elements the wire feed grippers are thus completely free of the wire and remain so till the wire feeding elements are again stationary and the next closure takes place prior to the ensuing feeding stroke. (3) The wire gripper control means to operate the grippers as described must be effective whatever the length of wire being fed within a given range of adjustment of the length of feed. (4) In double-stitch feed mechanism, the wire gripper control means to operate the grippers in the manner described must be constructed to operate the respective grippers of both wires to obtain simultaneous feed, and must be adaptable to operate when required only the wire feed grippers and non-return grippers of either one of the wires. (5) By virtue of the construction disclosed in the previous requirement, if by timed independent means the gripper actuating mechanism is prevented from acting on the grippers pertaining to one of the wires, and this latter wire is held continuously by its non-return gripper, whilst its feed gripper, is inoperative, the said wire will be immobilised and only single stitches will be driven from the other wire until the original control is restored and both wires are again fed simultaneously. If the above requirement is satisfied, suitable independent control mechanism may be employed to place any desired sequence of double or single stitches.

The feeding of wire from a spool is accomplished either by grip between actuated feed rollers or discs, or by gripper jaws guided in a straight or arcuate path. The invention may be utilised in any of these cases. It will be understood however that the construction will differ in detail with the range of adjustment of wire feed required and the type of wire feeding adopted, without however varying in principle or function.

By way of an example, an embodiment of the invention will now be described in more detail with reference to the accompanying drawings. In this example the invention is described as applied to a double stitch feed mechanism with arcuately guided grippers.

In the accompanying drawings: 55 Figure 1 is a partial front elevation, partly in

section, of a wire feed mechanism, with the front cover removed.

Figure 1a is a separate elevation of the cam mechanism, which is only partially shown in Figure 1.

Figure 1b is an extracted detail of Figure 1 in side elevation.

Figure 2 is a sectional end elevation on the line X—X of Figure 1 in the direction indicated.

Figure 3 is a partial sectional end elevation on the line Y—Y of Figure 1 in the direction indicated.

Figure 4 is a partial plan view on the line Z—Z of Figure 1.

Sufficient of the machine frame work and contiguous mechanism is shown in the figures, to make clear the relationship of the mechanism to be described.

Referring more particularly to Figures 1 and 1a, rotating in the direction indicated by the arrow C in the wire stitching machine frame 1, is a compound cam 2, the outer periphery 3 of which constitutes a cam surface for operating the wire gripper control means and the wire cutting and subsidiary mechanism to be described later. The periphery 4 of the rotating cam operates the wire feeding element which is in the form of a feed lever 12. The stitch forming and driving elements are also driven from the cam 2, and the general arrangement of these elements with respect to the cam may be substantially as described in British Patent Specification No. 361,633. The stitch forming element is indicated at 5.

Sliding in the stitching head frame, parallel to the stitch forming element 5, is a slider 6, which is also referred to as the wire gripper control element. This element is shown in the Figure 1 in section with its front connecting wall removed. The slider 6 is provided with a pin and cam roller 7 working in conjunction with the cam periphery 3 and actuated thereby in the manner to be described later. The cam roller 7 is urged against cam periphery 3 by a compression spring 6a and plunger 6b abutting at the lower end against a fixed part of the frame. The slider 6 carries a striker plate 8 rigidly secured thereto. The element 6 is hollowed out at the back to admit a forwardly projecting part of a horizontally adjustable sliding plate 9. This plate carries the upper and lower wire cutting knives indicated respectively by 9b and 9c and their supporting means and also a pair of non-return wire grippers 10 each adapted to hold one of the wires during the return motion of the wire feeding element. The relative disposition of the wire cutters and the plate 9 are not described in detail but are indicated in Figure 1. The non-return grippers 10 slide in vertical slideways formed in the projecting part of the adjustable sliding plate 9, as shown in Figure 3, and in whatever position the plate 9 may be set, these grippers and also the wire cutters are normally actuated by the wire gripper control element 6. In order that two wires may be operated on simultaneously or separately, the lower cutting element is duplicated and the upper cutting knife is adapted to cut both wires if these are presented to it, preferably in immediate succession instead of simultaneously. The non-return wire grippers 10 are independently slideable in the extension of plate 9 as shown in Figure 3, and have stems 11 projecting through the control element 6 for independent actuation as described later. Each stem 11 is capable of movement with respect to the gripper 10, to an extent limited by a pin 10a and a slot 10b, and is normally pressed

against the slider 6 by a spring 10c resiliently connecting the slotted stem 11 to the gripper 10.

The wire feeding means comprise a wire feed lever 12 pivoted on a fixed axis 13 in the machine frame and actuated by the cam periphery 4 through a cam roller 4a. The feed lever is urged clockwise by a spring 14. The lower arm of the feed lever 12 is adapted directly to carry the wire feeding grippers, of which there are two, each adapted to operate on one of the wires with its respective non-return gripper. The amount of wire fed in each stroke is regulated by the position in which the bracket 9a is set, this bracket being rigid with the plate 9. The position of bracket 9a determines also the position of the cut-off knives relative to the stitch forming and driving elements, and the position of an initially adjusted set screw 15, against which impinges a stop 16 mounted on the feed lever 12, and thereby determines the free motion of the feed lever 12 under the action of the spring 14. The wire feeding means also comprise a guide plate 17 having slots 17a for two wires, a wedge shaped channel 18 on either side of the lever 12, and two slotted grippers 19 working in the channels 18 and adapted to move on pins 19a carried by actuating levers 20. The levers 20 are separately pivoted on a pin 21 secured in the lever 12 and normally close the grippers under the influence of the springs 22.

To actuate the wire feed grippers the following mechanism is provided. Mounted on a fixed pivot 23 in the stitching head are two independent two armed levers 24 one on either side of the lever 12. A pin 25 in each of these levers serves to pivot links 26 the lower ends of which are provided with slots 27 embracing the pivot pin 21 of the levers 20 on either side of the lever 12. The links 26 also carry lugs 26a for setting screws 28, the ends of which abut against projections 20a of the levers 20. The pendant arm of each lever 24 has a projection 24a to co-act with the striker plate 8 secured to the wire feed control element 6.

The action of the mechanism so far described is as follows, and it will be understood that the action takes place similarly whether either or both wires are threaded up, in the latter case a succession of double stitches being formed and driven.

In the position shown in Figures 1 and 1a, the forward stroke of the wire feed lever 12 has been completed, the roller 4a being on the highest part of the cam 4. Also, the non-return grippers 10 have been pressed on to the wires D by the first rise 3a of the cam periphery 3 having depressed the roller 7 and hence the slider 6. Before the cam periphery 4 begins to allow the feed lever to return, the cam periphery 3 further depresses the slider 6, so that the striker plate 8 moves the levers 24 clockwise about 23 and therefore raises the links 26. By the medium of the setting screws 28 the levers 20 are turned counter-clockwise about 21 thus opening the wire feed grippers 19 against the action of the springs 22, and these grippers remain open during the whole of the return stroke of the feed lever 12, the wires being meantime under control of the non-return grippers 10, and held immovable thereby. The cam peripheries are designed such that when the feed lever 12 is fully returned (at the longest feed setting obtainable by adjustment of plate 9) the feed lever is stationary for a period before commencing the forward stroke. During this period the projection 3b of the cam periphery 3 further depresses the control member 6, causing the wire cutters 9b and 9c actuated thereby to cut the wires. Immediately thereafter the cam projec-

tion 3b allows the full return of the slider 6, which return motion first restores the wire feed grippers 19 into action on the wires, through the levers 24, links 26 and springs 22, and then opens the non-return grippers 10. The wires are now controlled only by the wire feed grippers 19 and the wire feeding stroke commences. When this is complete the portion 3a of cam periphery 3 again actuates the slider 6 to close the non-return grippers 10, both wire feed grippers and non-return grippers being now temporarily in action during a pause of the lever 12 at the end of the feeding stroke. The position shown in Figures 1 and 1a has now been regained and the cycle commences again.

The pivot center 25 is so disposed that up to the limiting position of the feed length adjusting bracket 9 farthest away from the stitching centre line, the wire feed grippers 19 remain clear of the wire during the entire return stroke until released by the cam projection 3b.

In general double stitches are only required in a specified sequence interspersed with single stitches. To enable either wire of a double wire stitcher to be put out of action as and when required, the following additional feed selector mechanism is provided.

Referring more particularly to Figure 4 a fixed pivot center 28 is provided on the stitching head framework, on which is pivoted in a horizontal plane a double armed lever 29. The forward extremity of this is provided with two longitudinal slots 29a in which a double pronged fork 30 is adjustably secured by screws 29b. The prongs are provided with sloping end faces 31, and these are adapted to engage the ends of the horizontal arms 24b of the respective levers 24 when the lever 29 is actuated.

When the fork 30 engages neither of the levers 24 no selective control is exercised and the sequence of double stitches already described takes place if both wires have been threaded up. When one prong of the fork is set to engage the rear lever 24, as shown in Figure 4, the rear wire is immobilised, whilst if set to engage the front lever 24 the front wire will be the one affected.

Referring back to Figures 1 and 1a, and assuming the member 30 is set as in Figure 4; when the element 29 is actuated to insert the parallel part of the prong beneath the projection 24b of the rear lever 24, the corresponding feed wire gripper 19 is opened through its link 26, and control of this gripper from the slider 6 through the striker plate 8 ceases. Further, by means of the projection 24c of the rear lever 24 and the projecting stem 11 of the rear non-return gripper 10, the latter is kept closed as long as this position of the fork 30 is maintained. This condition applies within the range of adjustment of plate 9. In other words the rear wire is no longer fed forward and remains held by the respective non-return gripper 10 which prevents any displacement thereof. This condition is maintained until normal control is restored by the reverse movement of the lever 29, which allows the lever 24 to return to its normal position where it is under the influence of the feed control member 6.

The lever 29 may be manually operated, or alternatively it may be coupled up to stitch setting mechanism so as to be automatically operated after a given sequence of stitches. For example such automatic operation may be realised by coupling the lever 29 through a member 32 to the mechanism described in the co-pending patent application No. 782,822.

It will be understood that the wire feed control mechanism according to the invention may be employed in wire stitching machines using forms of grippers other than those described above, for example in machines using feed wheels or discs to feed the wire, the carriers for one of each pair of discs would be operated to put the discs, whilst these are stationary, in and out of engagement with the wire in a functionally similar manner, the feed discs being in this case the wire grippers.

Furthermore it is to be understood that although the invention has been described herein as applied to a stitching machine it is not limited in this respect but only in so far as defined in the 15 appended claims.

We claim:

1. Mechanism for intermittently feeding wire comprising in combination a supporting frame, a wire feeding element, a driving cam for causing 20 said element to perform a feeding stroke and a return stroke with a stationary dwell period before each change of direction, a wire feed gripper supported by said feeding element and for gripping the wire during the feeding stroke, a non-return gripper for holding the wire stationary during the return stroke, a wire gripper control element common to both the feed gripper and non-return gripper, a cam follower on said common control element, a cam periphery associated with said driving cam engageable with said follower to displace said control element in timed relationship with said wire feeding element, and means for operatively connecting the control element to both the feed gripper and non-return 25 gripper, said cam periphery being shaped to displace the control element to open and close the respective grippers during the respective stationary dwell periods of the wire feeding element to ensure that full control of the wire is always taken over by one of the grippers before being relinquished by the other gripper.

2. Mechanism for intermittently feeding wire comprising in combination a supporting frame, a wire feeding element, a driving cam for causing 30 said element to perform a feeding stroke and a return stroke with a stationary dwell period before each change of direction, a wire feed gripper supported by said feeding element and for gripping the wire during the feeding stroke, a non-return gripper for holding the wire stationary during the return stroke, a wire gripper control element common to both the feed gripper and the non-return gripper, a cam follower on said common control element a cam periphery associated with said driving cam engageable with said follower to displace said control element in timed relationship with said wire feeding element, means for operatively connecting the common control element to both the feed gripper and the non-return gripper respectively at predetermined times during each cycle of movement of the wire feeding element, and parts on said cam periphery for displacing the control element and causing the latter to actuate the respective grippers so that control of the wire is transferred from one gripper to the other during the respective stationary dwell periods, said driving cam and the associated cam periphery being so arranged that each transfer includes a finite time 35 interval during which the wire is gripped by both the feed gripper and the non-return gripper.

3. Mechanism for intermittently feeding wire comprising in combination a supporting frame, a wire feeding element, a driving cam having a 40 periphery for causing said element to perform a

feeding stroke and a return stroke with a stationary dwell period before each change of direction, a wire feed gripper supported by said feeding element and for gripping the wire during the feeding stroke, a non-return gripper for holding the wire stationary during the return stroke, a vertically displaceable gripper control element common to both the feed gripper and the non-return gripper, means for providing operative connection between said common control element and the wire feed gripper over the full amplitude of movement of the wire feeding element, said means comprising a lever pivotally mounted in the frame and operable by said control element and a link operatively connecting said lever to the feed gripper, a cam follower on said common control element, a second periphery on said driving cam engageable with said follower for displacing the common control element along a vertical guide in the frame, the said peripheries of the driving cam being so shaped that the control element is displaced in timed relationship with the said wire feeding element to effect in each stationary dwell period firstly the closing of that gripper which is for the time being in the open position and thereafter the opening of the other gripper.

4. Mechanism for intermittently feeding wire comprising in combination a supporting frame, a wire feeding element, a driving cam having a periphery for causing said element to perform a feeding stroke and a return stroke with a stationary dwell period before each change of direction, a wire feed gripper supported by said element and actuated by lever mechanism pivotally connected to the feeding element, a non-return gripper for holding the wire stationary during the return stroke, a vertically displaceable gripper control element common to both the feed gripper and the non-return gripper, a striker on the control element for actuating said lever mechanism and feed gripper, means for operatively connecting the control element to the non-return gripper, fixed vertical guides in the frame for said common control element, a second periphery on said driving cam for displacing the common control element in said vertical guides against spring pressure and in timed relationship with said wire feeding element, the said lever mechanism providing operative connection between said common control element and the wire feed gripper over the full amplitude of movement of the wire feeding element.

5. Mechanism as claimed in claim 4, wherein the lever mechanism of the feed gripper comprises a lever pivotally mounted in the supporting frame, said lever having an arm operable by the striker of the common control element, a second lever operatively connected to said first lever, the second lever having control of the feed gripper over the full amplitude of movement of the wire feeding element.

6. A mechanism as claimed in claim 4, wherein the lever mechanism for actuating the wire feed gripper comprises a lever pivoted in the supporting frame, said lever having an arm operable by the striker of the common control element, an intermediate lever pivotally connected to the said first lever and controlling said wire gripper over the full range of movement of the wire feeding element, and a wire gripper lever connecting said intermediate lever to the wire feed gripper.

7. Mechanism for intermittently feeding wire comprising in combination a supporting frame, a driven shaft, a cam mounted on said driven

shaft, a wire feeding element, a periphery on said cam for driving the wire feeding element to perform a feeding stroke and a return stroke with a stationary dwell period before each change of direction, a wire feed gripper carried by a spring loaded lever pivotally mounted upon said feeding element, a non-return gripper for holding the wire stationary during the return stroke, a vertically displaceable gripper control element, a striker on said control element, a lever mechanism providing an operative connection between the control element and the wire feed gripper over the full amplitude of the feeding element, said mechanism comprising a lever pivoted on the frame, an arm on said lever engageable by the striker of the common control element, an intermediate arm pivotally connected at one end to said lever and, at the other end, slidably connected to the spring loaded lever which carries the feed gripper, means for operatively connecting the control element to the non-return gripper, a second periphery on said cam for displacing the control element against the action of a spring pressed plunger, in timed relationship with the actuation of the feeding element, each of the peripheries of said cam being so formed that the control element is displaced to open and close the respective grippers during the respective dwell periods of the wire feeding elements.

8. Mechanism for intermittently feeding wire comprising in combination a supporting frame, a wire feeding element having a cam follower at one end, a driving cam with a cam periphery engageable with said follower for causing said element to perform a feeding stroke and a return stroke with a stationary dwell period before each change of direction, a wire feed gripper pivotally mounted upon the other end of said element, a displaceable control element operatively connected to the wire feed gripper, a support member mounted within the frame and adjustable in the direction of wire feed, an extension on said support member projecting into the control element, a non-return gripper slidably mounted in said extension for holding the wire stationary during the return stroke of the feeding element, wire cutters carried by said extension of the support member, a cam follower on said control element, a spring urged plunger for holding said follower in engagement with a second periphery on said driving cam, parts on said second periphery for depressing the control element against the action of said plunger to cause the common control element to operate the wire feed gripper, the non-return gripper and the wire cutters, the peripheries on said driving cam being so arranged that the control element is actuated in timed relationship with respect to the wire feeding element to transfer the wire grip from one gripper to the other at intervals falling within the respective stationary dwell periods of the feeding element and to operate the wire cutters at a predetermined time in the working cycle over the adjustment range of the said adjustable support.

9. The mechanism as claimed in claim 8, comprising in combination, an adjustable stop on said support member, an abutment on the wire feeding element engageable with said stop at the end of the return stroke of said element, and means for adjusting said support member thereby to determine both the position of the wire cutters and also the length of stroke of the wire feeding element.

10. Mechanism for intermittently feeding wire comprising in combination a supporting frame, a

wire feeding element, a rotatable cam for driving the said element to perform a feeding stroke and a return stroke with a stationary dwell period before each change of direction, a wire feed gripper supported by said element for gripping the wire during the feeding stroke, a non-return gripper for holding the wire stationary during the return stroke, a wire gripper control element common to both the feed gripper and the non-return gripper, a cam follower on said common control element, a periphery on said rotatable cam engageable with said follower for displacing said control element in timed relationship with said wire feeding element, a linkage providing operative connection between common control element and the wire feed gripper over the full amplitude of movement of the wire feeding elements, means actuated by said control element for opening and closing the respective grippers during the stationary dwell periods of the wire feeding element, and wire feed interrupting means comprising a lever pivoted in the supporting frame, an arm on said lever engageable with said linkage to break the operative connection between the common control element and the wire feed gripper without effecting the motion of the wire feeding element and means for causing the said interrupting means to clamp the non-return gripper on the wire to immobilize the same.

11. The mechanism as claimed in claim 10, wherein the linkage providing operative connection between the common control element and the wire feed gripper, comprises a lever pivotally mounted in the machine frame, an arm on said lever, a striker on said common control element for engaging said arm rocking said lever upon downward displacement of said control element, a second arm on said lever for clamping the non-return gripper on the wire to immobilize the same, said second arm being normally held out of action during wire feeding, and a projection on said lever engageable by the wire feeding interrupting lever.

12. A mechanism for intermittently feeding wire comprising in combination a supporting frame, a driving cam mounted for rotation in said frame, a wire feeding element for feeding two wires simultaneously, a periphery on said driving cam for causing said feeding element to perform a feeding stroke and a return stroke with a stationary dwell period before each change of direction, two wire feed grippers each supported by said feeding element and movable simultaneously in the feed direction by the wire feeding element, lever mechanism for independently operating the said feed grippers for gripping and releasing the respective wires, two non-return grippers, one for each wire, mounted for independent operation for gripping and releasing the respective wires, a displaceable wire gripper control element common to the wire feed grippers and the non-return grippers, a second periphery associated with said driving cam, a cam follower on said common control element engageable with said second cam periphery for displacing the common control element in timed relationship with the wire feeding element to open and close the wire feed grippers in unison and to open and close the non-return

grippers in unison, projections on said cam peripheries for causing the opening and closing operations to take place during the respective stationary dwell periods of the wire feeding element, wire feed interrupting means comprising a lever pivotally mounted in the frame, a pair of arms on said lever each of which arms is associated with one of the wire feed grippers and its respective non-return gripper, and means for 5 rocking said wire feed interrupting lever to immobilize either one of the wires by clamping the respective non-return gripper on the wire and in the same action removing the respective wire feed gripper from the influence of the common control element.

13. The wire feed mechanism as claimed in claim 12, wherein the means for establishing operative connection between the common control element and the respective wire feed grippers 10 comprises for each wire feed gripper an independent mechanism comprising a lever pivotally mounted in the frame, a dependent arm on each of said levers, a striker on said common control element engageable with said dependent arms to 15 operate said levers for normal double wire feeding, and lateral arms on said levers independently engageable by said wire feed interrupting lever to immobilize one of said mechanisms to provide for single wire feeding.

14. A wire feeding mechanism as claimed in claim 12, wherein the lever mechanism for each feed gripper comprises a lever pivotally mounted in the frame and operatively connected to the respective gripper, a dependent arm on said lever 20 engageable by a striker on the common control element for the normal opening and closing of the gripper, a second arm on said lever engageable with a plunger connected to the respective non-return gripper, and a third arm operable by the interrupting means to cause said lever to open the respective wire feed gripper and to retain it in that position while said plunger is actuated by said second arm to cause the non-return gripper to immobilize the wire.

15. The mechanism as claimed in claim 14, wherein the wire feed interrupting means comprises a lever pivotally mounted in the frame for motion in a horizontal plane, a double pronged fork carried by said lever, one prong for each lever mechanism, and means for the selective displacement of said lever to cause a prong of said fork to engage the said third arm of the associated lever mechanism and to produce immobilization of the respective wire.
